United States Patent Office

Des. 208,109
Patented July 18, 1967

208,109

JUG

Stewart H. Birrell, Sylvania, and Raymon E. Hobbs,
Toledo, Ohio, assignors to Owens-Illinois, Inc., Toledo,
Ohio, a corporation of Ohio

Filed Sept. 16, 1966, Ser. No. 3,897

Term of patent 14 years

(Cl. D58—5)

FIG. 1

The characteristic features of this design reside in the configurations shown in full lines on the drawings.

We claim:

The ornamental design for a jug, substantially as shown and described.
